UNITED STATES PATENT OFFICE.

JOSEPH F. BREZINSKI, OF CHICAGO, ILLINOIS, ASSIGNOR OF ONE-HALF TO ANDREW OWCZARZAK, OF CHICAGO, ILLINOIS.

DAVENPORT-BED.

1,088,258.

Specification of Letters Patent. Patented Feb. 24, 1914.

Application filed August 23, 1913. Serial No. 786,246.

To all whom it may concern:

Be it known that I, JOSEPH F. BREZINSKI, a citizen of the United States, and a resident of the city of Chicago, county of Cook, and 5 State of Illinois, have invented certain new and useful Improvements in Davenport-Beds, of which the following is a specification.

My invention relates to improvements in 10 davenport beds, and has for its object the production of a device of this character which may be readily and easily converted from a davenport to a bed or vice versa, and which will be of durable and economical construction.

Other objects will appear hereinafter.

The invention consists in the combinations and arrangements of parts hereinafter described and claimed.

20 The invention will be best understood by reference to the accompanying drawings forming a part of this specification, and in which,

Figure 1 is a vertical longitudinal section 25 of a davenport bed embodying my invention, the same being shown converted into a bed, Fig. 2 is a similar section showing the device arranged for use as a davenport, Fig. 3 is an enlarged detail section taken on line $\alpha-\alpha$ of Fig. 1, Fig. 4 is a horizontal section taken on line $y-y$ of Fig. 1, and Fig. 5 is a rear elevation of the construction shown in Fig. 2.

The preferred form of construction as 35 illustrated in the accompanying drawings comprises a body or frame consisting of end members 1 which are rigidly connected at their forward and rearward ends or edges by cross pieces 2 and 3 respectively. 40 Hinged at 4 to the upper rear corners of the end members 1 is a transversely extending member 5 to the forward edge of which is hingedly secured at 6 the upper edge of a back member 7, the front side of the latter being suitably upholstered. The back member 7 is so mounted as to permit of forward 45 and upward swinging thereof to a position as shown in dotted lines in Fig. 1, said back member being releasably held in this position by means of a supporting rod 8 one end of which is pivotally connected with the rearward side of said back member. The

opposite or free end of the supporting rod 8 loosely engages a strap 9 secured to the inner side of the corresponding end member 1, 55 a notch 10 provided in one edge of said member 8 being adapted to releasably engage a pin 11 arranged at said strap 9 to releasably support the back member 7 as above mentioned. When it is desired to lower the 60 back member 7 to its normal vertical position it is only necessary to release notch 10 from engagement with pin 11 whereupon said back member will swing downwardly by gravity to the desired position. 65

Pivottally mounted at 12 upon the inner sides of the end members 1 are arms or levers 13 of angular or curved form. Corresponding ends of arms 13 are rigidly connected at 14 with a bed bottom consisting of 70 bed sections 15 and 15' which are foldably connected by links or connecting elements 16, the arms 13 being connected with the section 15. A foldable bed bottom is thus constituted, the sections 15 and 15' being 75 adapted to be folded upon one another as indicated in Fig. 2 and to be unfolded into coplanar operative positions, as shown in Fig. 1. When in unfolded or operative condition, the center of the bed bottom is reinforced by cross bars 17 the 80 central portions of which are bent downwardly, as clearly shown in Fig. 5 so as to permit the depression or slight sagging of the bed bottom when in use. When the bed 85 bottom is in extended condition the inner end of section 15 is supported by levers 13, the outer end thereof being supported by legs 18 which depend therefrom into engagement with the cross piece 2, as clearly 90 shown in Fig. 1. Also in this arrangement the outer end of section 15' is supported by legs 19 which are foldably connected with said bed section so that when the latter is in folded position, said legs may be swung upwardly into the same plane therewith, as clearly shown in Fig. 2.

Arranged at the rearward end of the bed section 15 is a spring catch 20 adapted, when the bed bottom is in folded condition, to 100 engage the free edge of section 15' in order to hold the same in close proximity with the section 15, as clearly shown in Fig. 2. When the device is converted into a bed the spring

catch 20 serves in the capacity of a stop for the lower edge of the back member 7 holding the latter in position to adapt the same to constitute a pillow rest.

5 When the device is used as a davenport the bed bottom, in folded condition, is swung to vertical position and confined behind the back member 7. In this arrangement the back 7 serves as a means for preventing forward 10 swinging of the bed bottom, rearward swinging of the latter being prevented by angular stop pieces 21 secured to the under side of cross piece 5 at the rearward edge thereof. Also arranged between the end 15 members 1 is a seat member 22 the rearward end of which is pivotally connected at 23 with corresponding ends of arms 13, the latter thus serving as supports for said end of said seat member. The forward end of said member 22, when the device is used as a 20 davenport, is supported upon the cross piece 2, as clearly shown in Fig. 2. Secured to the inner sides of end pieces 1 extending rearwardly from the upper edge of cross 25 piece 2 are inclined angle irons 24 which serve as supports for the forward edge of the seat member when the latter is moved rearwardly as is the case when the bed bottom is unfolded into operative position, it 30 being clear that upon swinging of section 15 forwardly and downwardly to horizontal position the rearward edge of seat member 22 will be moved rearwardly and downwardly to the position shown in Fig. 1. In 35 this movement of said seat member the forward edge thereof will ride downwardly upon the supporting members 24 and, so that when the bed bottom is in operative position, said seat member will be positioned below 40 the same, as shown in Fig. 1. Conversely when the bed bottom is folded and swung to inoperative position the seat 22 is automatically moved forwardly and upwardly to operative position as shown in 45 Fig. 2.

With a construction as set forth, when it is desired to convert the same from a davenport to a bed, it is first required to swing the back member 7 to the elevated position shown 50 in dotted lines in Fig. 1. In this swinging of said back member the upper end of the folded bed bottom will be moved forwardly by the stop members 21 so as to be readily engageable for forward swinging and unfolding. In the forward swinging and unfolding of the bed member the seat 22 of the davenport is automatically lowered to inoperative position as just described. The bed is completed by lowering the back member 55 7 to the position shown in Fig. 1, in which position of said back member a pillow rest is constituted. The reverse operations are of course resorted to in converting the device from a bed into a davenport.

60 65 The construction is durable and economi-

cal and the manipulation thereof may be readily and easily effected.

While I have illustrated and described the preferred form of construction for carrying my invention into effect, this is capable of 70 variation and modification without departing from the spirit of the invention. I, therefore, do not wish to be limited to the precise details of construction set forth, but desire to avail myself of such variations and 75 modifications as come within the scope of the appended claims.

Having described my invention what I claim as new and desire to secure by Letters Patent is:

1. A construction of the class described comprising end members; a back member pivoted between said end members to swing upwardly; a bed member mounted upon swinging arms and adapted, when in inoperative position, to be positioned beneath said back member; and a seat member pivotally connected with said arms and adapted, when said bed member is in operative position, to be lowered to a position behind said bed member, substantially as described. 80

2. A construction of the class described comprising end members; a back member pivoted between said end members to swing upwardly; a bed member mounted upon swinging arms and adapted, when in inoperative position, to be positioned behind said back member; and a seat member pivotally connected at its rearward end with said arms and having its forward end loosely supported, said seat member, when said bed member is moved to operative position, being automatically moved to a position below said bed member, substantially as described. 95

3. A construction of the class described comprising end members; a back member pivoted between said end members to swing upwardly; a bed member mounted upon swinging arms and adapted, when in inoperative position, to be positioned behind said back member; a seat member pivotally connected at its rearward end with said arms; and inclined surfaces for the forward end of said seat member, said seat member when said bed member is moved to operative position, being automatically moved rearwardly and downwardly to a position below said bed member, substantially as described. 105

4. A construction of the class described comprising end members; a back member pivoted between said end members to swing upwardly; a pair of arms pivotally mounted intermediate their ends upon said end members; a bed member rigidly mounted upon corresponding ends of said arms and adapted to be swung to inoperative position behind said back member; and a seat member, pivotally connected with the opposite ends of said arms whereby, when said bed member is 115 swung to operative position, said seat mem- 120 ber is moved to a position beneath said back member. 125

ber will be lowered to a position below said bed member, substantially as described.

5. A construction of the class described comprising end members; a back member pivoted between said end members to swing upwardly; a pair of arms pivotally mounted intermediate their ends upon said end members; a bed member rigidly mounted upon corresponding ends of said arms and 10 adapted to be swung to inoperative position behind said back member; a seat member having its rearward end pivotally connected with the opposite ends of said arms whereby, when said bed member is swung to operative 15 position, said end of said seat member will be moved downwardly and rearwardly to a position below said bed member; and supporting means for the front end of said seat member permitting of movement thereof 20 corresponding with that of said rearward end, substantially as described.

6. A construction of the class described comprising end members; a back member pivoted between said end members to swing upwardly; a pair of arms pivotally mounted intermediate their ends upon said end members; a bed member rigidly mounted upon corresponding ends of said arms and adapted to be swung to inoperative position behind said back member; a seat member having its rearward end pivotally connected with the opposite ends of said arms whereby, when said bed member is swung to operative position, said end of said seat member will be moved downwardly and rearwardly to a position below said bed member; and inclined surfaces for the front end of said seat member whereby said front end of said seat member will move correspondingly with the rearward end thereof, substantially as described.

7. A construction of the class described comprising end members; a back member pivoted between said end members to swing upwardly; a bed member mounted upon swinging arms and adapted, when in operative position, to be positioned horizontally between said end members; a seat member pivotally connected with said arms and 50 adapted, when said bed member is in operative position, to be lowered to a position beneath said bed member; said back member, when said bed member is in operative position, constituting a pillow rest; and means 55 for limiting the rearward swinging of said back member when the same is serving as a pillow rest, substantially as described.

8. A construction of the class described comprising end members; a back member 60 pivoted between said end members to swing upwardly; a bed member mounted upon swinging arms and adapted, when in operative position, to be positioned horizontally between said end members; a seat member pivotally connected with said arms and

adapted, when said bed member is in operative position, to be lowered to a position beneath said bed member, said back member, when said bed member is in operative position, constituting a pillow rest; and a stop 70 on said bed member for limiting the rearward swinging of said back member when the same is serving as a pillow rest, substantially as described.

9. A construction of the class described comprising end members; a back member pivoted between said end members to swing upwardly; a bed member mounted upon swinging arms and adapted, when in operative position, to be positioned behind said back member; a seat member pivotally connected with said arms and adapted, when said bed member is in operative position, to be lowered to a position beneath said bed member; and means for releasably holding said back member in elevated position to permit of swinging of said bed member, substantially as described.

10. A construction of the class described comprising end members; a back member pivoted between said end members to swing upwardly; a bed member mounted upon swinging arms, said bed member when in inoperative position, being positioned behind said back member and held by the latter against forward swinging; means for locking said bed member against rearward swinging when in inoperative position; and a seat member pivotally connected with said arms whereby, when said bed member is 100 swung to operative position, said seat member will be lowered to a position below said bed member, substantially as described.

11. A construction of the class described comprising end members; a back member pivoted between said end members to swing upwardly; a foldable bed member mounted upon swinging arms, said bed member, when folded and in inoperative position, being positioned behind said back member and held by the latter against forward swinging; means for locking said bed member against rearward swinging when in operative position; and a seat member pivotally connected with said arms whereby, when said bed 110 member is swung to operative position, said seat member will be lowered to a position below said bed member, substantially as described.

12. A construction of the class described comprising end members; a back member pivoted at its upper end between said end members to permit of upward swinging of the lower end thereof; a bed member mounted upon swinging arms, said bed member, when in inoperative position, being positioned behind said back member and held by the latter against forward swinging; stops provided at the upper end of said back member, said stops, when said back member 125

is swung upwardly, moving the upper end of said bed member forwardly; and a seat member pivotally connected with said arms, whereby, when said bed member is swung 5 to operative position, said seat member will be lowered to a position below said bed member, substantially as described.

In testimony whereof I have signed my name to this specification in the presence of two subscribing witnesses.

JOSEPH F. BREZINSKI.
